CLAIM

The ornamental design for a golf training aid, as shown and described.

DESCRIPTION

FIG. 1 is a top, back, left-side perspective view of a golf training aid;

FIG. 2 is a bottom, front, left-side perspective view thereof;

FIG. 3 is a front view thereof;

FIG. 4 is a back view thereof;

FIG. 5 is a left-side view thereof;

FIG. 6 is a right-side view thereof;

FIG. 7 is a bottom view thereof;

FIG. 8 is a top view thereof; and,

FIG. 9 is an environmental perspective view thereof.

The dashed broken lines depict portions of the golf training aid and environment that form no part of the claimed design.

1 Claim, 6 Drawing Sheets
